UNITED STATES PATENT OFFICE.

GEORGE H. GILMAN, OF CLAREMONT, NEW HAMPSHIRE, ASSIGNOR TO SULLIVAN MACHINERY COMPANY, OF BOSTON, MASSACHUSETTS, A CORPORATION OF MASSACHUSETTS.

PRESSURE-FLUID MOTOR.

1,250,932.

Specification of Letters Patent. Patented Dec. 18, 1917.

Application filed March 30, 1914. Serial No. 828,155.

To all whom it may concern:

Be it known that I, GEORGE H. GILMAN, a citizen of the United States, and a resident of Claremont, Sullivan county, New Hampshire, have invented an Improvement in Pressure-Fluid Motors, of which the following description, in connection with the accompanying drawings, is a specification; like characters on the drawings representing like parts.

My invention relates to pressure fluid motors, which may be of the impact type, and more particularly to the valve mechanism for controlling the admission of the motive fluid to and exhaust from the cylinder.

My invention will be best understood by reference to the following specification, when taken in connection with the accompanying drawings of one illustrative embodiment thereof, while its scope will be more particularly pointed out in the appended claims.

In the drawings:

Figure 1 is a central, longitudinal sectional view, partly broken away, of a pressure fluid impact motor embodying one form of my invention;

Fig. 2 is a sectional view, partly broken away, on line 2—2 of Fig. 1;

Fig. 3 is a sectional view on line 3—3 of Fig. 1; and

Figs. 4 and 5 are diagrammatic sectional views, in which all of the ports and passages are brought into one plane, the better to illustrate the action of the motor; Fig. 4 showing the piston in its forward position and the valve in its rearward position; and Fig. 5 showing the piston in its rearward position and the valve in its forward position.

Referring to the drawings, and to the embodiment of my invention which I have selected for illustration, I have there shown a pressure fluid motor having a cylinder 6, in which a piston 7 reciprocates. This piston may be, and in the present instance is, provided with a forwardly projecting reduced portion 8, which may constitute a piston rod to be connected to the working device to be actuated, or the reduced portion may be used as a hammer to deliver a succession of blows against any suitable impact receiving member, which it is unnecessary herein to illustrate, as it forms no essential part of my present invention.

The movements of the piston are controlled by a controlling valve 9, herein in the form of a cylindrical shell located in a valve chamber, herein disposed at the rear of the cylinder chamber, and in line therewith, such valve chamber being herein provided by a two-part valve block composed of a forward section 10 and a rear section 11. Both sections of the valve block are seated within the walls of a suitable casing 12, which projects from a head-block 13, the rear portion of the latter being broken away. The head-block is provided with a supply chamber 14 for the motive fluid, to which the latter is constantly admitted from any suitable source of supply through a supply passage 15.

For the admission of motive fluid to the rear of the cylinder chamber, the valve chamber is provided with an annular admission groove 16, which has constant communication with the supply chamber 14, through a rearwardly extending passage or passages 17.

When in its rearward position (see Fig. 5), the rear end of the valve enters that portion of the valve chamber behind the admission groove 16, thereby cutting off the interior of the valve and the rear of the cylinder chamber from the motive fluid. In the forward position of the valve, however (see Figs. 1 and 4), the interior of the valve is opened freely to the admission groove 16, so that the motive fluid flows freely to the interior of the valve, and thence to the rear of the cylinder chamber to drive the piston forward.

The forward end of the cylinder chamber is supplied with motive fluid when the valve is at its rearward position (see Fig. 5), by means of one or more, herein two, return pressure passages 18, which extend longitudinally through the walls of the cylinder and open into the cylinder chamber through a lateral port 19. At its rear end, this passage extends through the valve block section 10, and terminates in a lateral port 20 formed in the valve block 11 and opening into an annular valve block groove 21.

In the rearward position of the valve, the groove 21 is connected with the motive fluid supply by means of a circumferential valve groove 22, the admission groove 16 being cut away at 23, adjacent one or more of the admission passages 17 (see Figs. 1, 110

4 and 5), so as to give a sufficiently free admission of motive fluid to the groove 21, by way of the valve groove 22, to return the piston. From the groove 21, the motive fluid passes through the port 20, passages 18 and port 19, to the forward end of the cylinder.

To exhaust motive fluid from the rear of the cylinder chamber, there is provided in the valve block a lateral exhaust port 24, which opens into the valve chamber. This lateral exhaust port communicates with one or more, herein three, longitudinal exhaust passages 25, formed partly in the cylinder walls and extending rearwardly through both sections of the valve block, and communicating with a permanently open exhaust port, or ports, 26 formed in the head block.

20 The valve is provided with a circumferential enlargement 27 working in an annular chamber or groove 28 of the valve chamber, the valve block being provided with a lateral exhaust port 29 leading from said groove to the exhaust passage 25. When the valve is in its rearward position (see Fig. 5), a prolonged portion 30 of the valve, which extends beyond the circumferential enlargement 27, lifts from its seat sufficiently 25 to open the rear of the cylinder chamber to the forward end of the valve chamber, thus placing the rear of the cylinder chamber in communication with the exhaust port 24. As shown in the drawings, the port 24 is 30 only partially uncovered by the valve when in this position, but such port may be, and preferably is, of an elongated cross section (see Fig. 2), so that by suitably proportioning the port, the exhaust from the rear of the cylinder chamber may be made as free or restricted as desired.

To exhaust motive fluid from the forward end of the cylinder chamber, the latter is provided with an exhaust port 31, adapted 45 to be uncovered by the piston before the completion of the rearward movement thereof, such port being connected with the longitudinal exhaust passages 25, and thereby with the atmosphere through the permanently open exhaust opening 26. In addition to this, the forward end of the cylinder is maintained open for the exhaust of motive fluid during the forward movement of the piston, after the closure of the port 31 50 through the return port 19, passage 18, and port 20, the latter being connected through the valve chamber, when the valve is positioned as shown in Fig. 4, with the valve groove 22, chamber 28, and exhaust port 29.

60 Referring now more particularly to the provision for moving the valve to reverse the piston, the valve is provided with a rear end portion 32 of slightly reduced diameter having a sliding fit in the corresponding reduced portion 33 of the valve chamber, be-

yond the admission groove 16. This leaves a small, circumferential shoulder 34, which constitutes a small pressure area constantly exposed to the motive fluid in the admission groove 16. On the other hand, the forward face of the circumferential enlargement 27 constitutes an opposing differential pressure area, of relatively greater proportions.

When the valve is in its forward position (see Figs. 1 and 4), the same is maintained in such position during the forward movement of the piston by the pressure on the small area 34, augmented by the pressure on the rear end area 35 of the valve, there being no substantial pressure against the larger opposing pressure area in the forward end of the chamber 28. To insure the absence of substantial pressure against this larger area at this time, there is herein provided a lateral port 36 leading from the forward end of the chamber 28 to a longitudinal passage 37, extending forwardly through the cylinder wall, and having at its forward end a port 38, which is in communication through the forward portion of the cylinder chamber with the exhaust port 31 and exhaust passage 25 leading to the permanently open exhaust opening 26. When the piston is moving forwardly, and up to the time when it reaches the port 38, the port 36, passage 37 and port 38, serve to exhaust any pressure fluid trapped in the forward end of the chamber 28, or entering thereinto by leakage from the cylinder chamber.

When, however, the piston, during its forward stroke, passes beyond and cuts the port 38 off from communication with the exhaust port 31, the passage 37 and port 36 are utilized to supply pressure fluid to the forward end area of the enlargement 27, to cause a reversal of the valve. To this end, the passage 37 is provided with a lateral port 39, to which it will be convenient to refer as the intermittent pressure port, for the reason that pressure fluid is intermittently supplied thereto to cause the reversal of the valve. Located substantially in line with this intermittent pressure port, is a constant pressure port 40, the latter communicating constantly through a longitudinal passage 41 and lateral port 42 with one of the rearwardly extending passages 17 leading to the constant pressure space 14.

As a means for intermittently establishing communication between the constant pressure port 40 and the intermittent pressure port 39, the piston is herein provided with a passage, herein in the form of an annular groove 43, which is so positioned that when it aligns with the constant pressure port and the intermittent pressure port, pressure fluid passes to the front end of the chamber 28 and, acting on the forward end of the enlargement 27, throws the valve to the rear.

This may take place at any suitable point, but preferably occurs just prior to the striking of the blow. The reversal of the valve takes place, owing to the fact that the pressure upon the large opposing differential area exceeds that on the small area 34 plus the end area 35 of the valve, and thus causes the latter to be quickly shifted to the position shown in Fig. 5. As above described, 10 this admits motive fluid to the forward end of the cylinder chamber, and opens the rear end thereof to the exhaust so that the piston, having made its working stroke, moves back on its return stroke.

15 The piston carries, projecting from its rear end, a plug portion 44, which in the illustrated embodiment of my invention, is of lesser diameter than the piston itself. This plug portion is adapted to project out 20 of and beyond the cylinder chamber in the rearward position of the valve, and through an aperture 45 in the valve plug, in which it preferably has a sliding fit, and which constitutes the means of communication between the valve chamber and the piston chamber.

The valve having been reversed, the piston during its return movement expels the exhaust motive fluid at the rear of the cylinder chamber, through the exhaust port 24. 30 During this movement of the piston, the supply of motive fluid to the chamber 28 is continued for a time, or until the forward edge of the piston groove 43 has passed rearwardly beyond the intermittent pressure port 39, thus cutting off the latter from the constant pressure port 40. Air under pressure is now trapped in the passage 37, port 36, and chamber 28, which, acting against the 35 forward area of the enlargement 27 and in conjunction with the exhaust pressure acting on the forward end of the reduced portion 30 of the valve, continues to hold the latter in its rearward position. When, however, the forward end of the piston, in its 40 rearward travel, reaches the intermittent pressure port 39, the latter is placed in communication with the forward exhaust port 31, whereby the pressure on the large differential area of the enlargement 27 of the 45 valve is exhausted.

The valve is thus held reversed preferably after the plug portion 44 enters the aperture 45. When the piston, however, reaches some such position as is represented in Figs. 1 and 4, (the valve still being in the position shown in Fig. 5), a fluid cushion is formed between the end of the piston and the opposing face of the valve block, by 50 reason of the closure of the aperture 45 by the portion 44 entering the same. This brings the piston to rest, and prevents it from striking the valve block, should the valve fail to reverse. About the same time, 55 however, the remaining motive fluid having

been substantially expelled, the pressure of the discharging exhaust against the forward end area of the valve and that of the motive fluid trapped in the chamber 28 is reduced to such a low point that the valve is quickly 70 reversed by the superior pressure acting upon the small pressure area 34.

As above described, this admits pressure fluid from the admission groove 16, driving the piston forward. At the same time, the 75 forward end of the piston chamber, which has been previously opened to the exhaust by the uncovering of the exhaust port 31, is also opened to the exhaust valve through the chamber by way of the port 19, return passage 18, port 20, valve groove 22, chamber 28, and port 29, this condition holding until the valve is again reversed. The valve, when reversed, is securely held in its forward position, since the port 36, passage 37, and 80 port 38, relieve the larger pressure area of the pressure of any accumulated motive fluid.

While the length of the projecting plug portion 44 might be reduced so as not to 90 project within the valve in the rearmost position of the piston, herein, for the sake of reducing the clearance within the valve chamber, it is somewhat prolonged as shown in the drawings, so that it not only passes 95 through and closes the port-like aperture 45, but also enters part way into the valve itself. The interior diameter of the valve, however, is made slightly greater than the exterior diameter of the plug, so that a 100 small clearance space remains between the valve and the entering portion of the plug. This permits the motive fluid trapped within the valve chamber to escape back and about the sides of the plug to the exhaust port 24, 105 when the plug enters the valve. Such escape, moreover, may be facilitated, if desired, by any suitable formation of the plug, such for example as the provision of one or more longitudinal grooves 46, cut part way along 110 the surface of the plug. These grooves, moreover, have another function which is of considerable importance. When the piston starts upon its forward movement, motive fluid acts against the area of the plug 44, 115 but when the forward ends of the grooves 46 pass forwardly beyond the aperture 45 and enter the rear portion of the cylinder chamber, the latter immediately receives motive fluid through the grooves, and such motive fluid at once acts upon the full area of the piston, thereby insuring a quick and powerful action at the part of the stroke where it is most needed.

The described form of valve, being very 125 delicately balanced, acts quickly to reverse at the close of the rearward piston movement, so that a very high speed and very powerful blow can be secured through its employment. Moreover, the clearance in 130

the cylinder and valve chamber being reduced to a minimum, a very high efficiency can be obtained.

It will be observed that the valve being located in a separate chamber, behind the piston chamber and between the latter and the head-block, it is not necessary for the operation of the tool that any part of the piston enter the valves. Herein, the plug 44, carried by the piston, is caused to enter the valve chamber to reduce the clearance therein, but such is not essential. The clearance within the valve chamber might be reduced by making the valve solid except for a central axial passage through the same, or with a valve proportioned as shown, a stationary plug might be employed projecting forwardly within the valve from the valve block section 11.

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.

Having thus described one embodiment of my invention, what I claim and desire by Letters Patent to procure is:—

1. A pressure fluid motor having an annular valve provided with two annular projections of different diameters providing differential pressure areas, a rearward extension extending rearwardly from the smaller pressure area, a forward extension extending forwardly from the larger pressure area; means for supplying motive fluid constantly to said smaller area; a chamber in which the larger annular projection works; means including a constant pressure port, an intermittent pressure port, a passage leading from said intermittent pressure port to said chamber, and a piston having a groove to connect said ports for intermittently supplying motive fluid to and exhausting it from said chamber thereby to cause the larger pressure area intermittently to predominate over the smaller thereby to effect the reversal of the valve; means for supplying motive fluid to the interior of said valve at its rear end to drive said piston forward; means controlled by said valve for supplying motive fluid to the forward end of said piston to drive it rearward; means to exhaust the forward end of said piston during its forward stroke; means controlled by said valve to exhaust the rear end of said piston during its rearward stroke.

trolled by said valve to exhaust the rear end of said piston during its rearward stroke.

2. A pressure fluid motor having an annular valve provided with differential pressure areas, a forward extension extending beyond the larger pressure area, a rearward extension extending beyond the smaller pressure area; means for supplying motive fluid constantly to said smaller area; means including a constant pressure port, an intermittent pressure port, and a piston having a groove to connect said ports for intermittently supplying motive fluid to and exhausting it from said larger pressure area; means for supplying motive fluid to the interior of said valve at its rear end to drive said piston forward; means controlled by said valve for supplying motive fluid to the forward end of said piston to drive it rearward; means to exhaust the forward end of the piston during a part of its forward stroke; means controlled by said valve to exhaust the forward end of said piston during a remaining part of its forward stroke; and means controlled by said valve to exhaust the rear end of said piston during its rearward stroke.

3. A pressure fluid impact motor having a hollow valve 9 provided with the enlargements 27 and 34 and the forward and rearward extensions; the piston 7 provided with the groove 43; and the cylinder provided with the constant pressure space 14; the valve chamber with its extension 33; the groove 28 in which the enlargement works; the passage 37 with its ports 36, 38 and 39; the passage 18 with its ports 19 and 20; the passage 41 with its port 40; the exhaust passage 25 with its port 31; and the exhaust ports 24 and 29.

4. A pressure fluid motor having a piston; an annular valve provided with differential pressure areas, a forward extension extending beyond the larger pressure area, a rearward extension extending beyond the smaller pressure area, a pocket 33 for said rearward extension; means for supplying motive fluid constantly to said smaller area; means including a constant pressure port, an intermittent pressure port and a groove 43 in said piston to connect said ports for intermittently supplying motive fluid to and exhausting it from said larger pressure area; means for supplying motive fluid to the interior of said valve at its rear end to drive said piston forward; means controlled by said valve for supplying motive fluid to the forward end of said piston to drive it rearward; means to exhaust the forward end of the piston; and means controlled by said valve to exhaust the rear end of said piston during its rearward stroke.

5. A pressure fluid motor having a piston; an annular valve provided with differential pressure areas, a forward extension extending beyond the larger pressure area,

- a rearward extension extending beyond the smaller pressure area, a pocket 33 for said rearward extension; means for supplying motive fluid constantly to said smaller area; 5 means including a constant pressure port, an intermittent pressure port and a groove 43 in said piston to connect said ports for intermittently supplying motive fluid to and exhausting it from said larger pressure area; means for supplying motive fluid to the interior of said valve at its rear end to drive said piston forward; means controlled by said valve for supplying motive fluid to the forward end of said piston to drive it 10 rearward; means controlled by said valve to exhaust the forward end of the piston; and means controlled by said valve to exhaust the rear end of said piston during its rearward stroke.
- 20 6. A pressure fluid motor having a piston provided with a reduced rearwardly disposed extension; an annular valve surrounding said reduced rearwardly disposed extension and provided with differential pressure areas, a forward extension extending beyond the larger pressure area; means for supplying motive fluid constantly to the smaller area; means including a constant pressure port, an intermittent pressure port 25 and a groove 43 in said piston to connect said ports for intermittently supplying motive fluid to and exhausting it from said larger pressure area; means for supplying motive fluid to the interior of said valve at its rear end to drive said piston forward; means controlled by said valve for supplying motive fluid to the forward end of said piston to drive it rearward; means to exhaust the forward end of the piston; and 30 means controlled by said valve to exhaust the rear end of said piston during its rearward stroke.
- 35 7. A pressure fluid motor having a piston; an annular valve provided with differential pressure areas, a forward extension extending beyond the larger pressure area, means for supplying motive fluid constantly to the smaller pressure area; means including a constant pressure port, an intermittent 40 pressure port, and a groove 43 in said piston to connect said ports for intermittently supplying motive fluid to and exhausting it from said larger pressure area; a constantly open exhaust port for exhausting such pres-
- sure fluid as is opposed to shifting of said valve by pressure on said larger pressure area; means for supplying motive fluid to the interior of said valve at its rear end to drive said piston forward; means controlled by said valve for supplying motive fluid to the forward end of said piston to drive it rearward; means to exhaust the forward end of the piston; and means controlled by said valve to exhaust the rear end of said piston during its rearward stroke. 45
8. A pressure fluid motor comprising in combination a cylinder, a piston therefor having a rearwardly extending reduced portion, an annular valve having a longitudinally disposed opening therein into which said reduced portion enters during a portion of the return stroke of said piston, and live pressure fluid actuated means for moving said valve alternately into two positions and for holding said valve in each of said positions pending reversal of said valve by said live pressure fluid actuated means. 50
9. A pressure fluid impact motor having a piston; its cylinder; an annular valve; means to cause said valve to be moved in opposite directions by live pressure fluid; means for closing the rear end of said valve in its rearmost position; means for causing motive fluid to pass through said valve to drive said piston forward when said valve is in its forward position; means under the control of said valve for exhausting the motive fluid from the rear of said piston; means for exhausting the motive fluid from the front end of said piston during a portion of its forward stroke including an exhaust port in the main wall of the cylinder independent of said valve and adapted to be closed by said piston during the forward stroke thereof; and supplemental means under the control of said valve for exhausting the motive fluid from the front end of said piston after the closure of said exhaust port during a remaining portion of the forward stroke of said piston. 55
- 100 In testimony whereof, I have signed my name to this specification, in the presence of two subscribing witnesses.
